COMBINED PACKAGING CARD AND HANGER FOR AN ARTICLE OF MERCHANDISE

Charles A. Wells, Coshocton, Ohio, assignor to Pretty Products, Inc., Coshocton, Ohio

Filed Oct. 19, 1973, Ser. No. 407,799

Term of patent 14 years

Int. Cl. D9—99

U.S. Cl. D9—291

FIG. 1 is a perspective view of a combined packaging card and hanger for an article of merchandise embodying this design illustrated in association with a device thus packaged and suspended from a hanger bar, both device and hanger bar being shown in broken lines for illustrative purposes only.

FIG. 2 is a front elevational view.

FIG. 3 is an end elevational view on an enlarged scale of the right hand end of the device as seen in FIG. 2.

FIG. 4 is an end elevational view on an enlarged scale of the left hand end of the device as seen in FIG. 2.

I claim:

The ornamental design for a combined packaging card and hanger for an article of merchandise, substantially as shown and described.
